(57) **CLAIM**

An ornamental design for a vehicle wheel cover, as shown and described.

DESCRIPTION

FIG. 1 is a front view of a vehicle wheel cover;

FIG. 2 is a perspective view of the vehicle wheel cover; and,
FIG. 3 is a side view of the vehicle wheel cover.

In the drawings, the broken lines showing portions of the hub area and rear of a vehicle wheel cover form no part of the claimed design.
